Patented Apr. 10, 1923.

UNITED STATES PATENT OFFICE.

ALFRED S. BOYLE, OF CINCINNATI, OHIO.

FLOOR WAXER AND POLISHER.

Application filed February 25, 1922. Serial No. 539,309.

To all whom it may concern:

Be it known that I, ALFRED S. BOYLE, a citizen of the United States of America, and a resident of Cincinnati, in the county of 5 Hamilton and State of Ohio, have invented a new and useful Improvement in a Floor Waxer and Polisher, of which the following is a specification.

An object of my invention is to provide 10 a floor polishing and waxing device that will not require the operator to exert any appreciable downward pressure upon the handle, but will by its own weight supply sufficient frictional contact with the surface 15 being waxed or polished, so that the operator need apply only the force necessary to propel the device over the surface being treated.

Another object of my invention is to provide a device of the type referred to, where- 20 in the elements bear such relation that accidental contact of the polisher with furniture will not mar or scratch the furniture.

Another object of my invention is to provide improved means for mounting and de- 25 taching waxing and polishing cloths upon the device.

Another object of my invention is to pro- 30 vide a device for the purpose stated that is simple in construction and assembly.

These and other objects are obtained by 35 means described herein and disclosed in the accompanying drawings, in which:

Fig. 1 is a perspective view, parts being broken away, of a device embodying my in- 40 vention.

Fig. 2 is a longitudinal sectional view, on an enlarged scale, of the device shown in Fig. 1.

Fig. 3 is a sectional view on line 3-3 of 45 Fig. 2, on a slightly reduced scale.

The device of my invention comprises a base consisting of a bottom plate 4 having a depression 5 formed in its upper face, the depression being bounded by an upwardly 50 extending flange 6 extending around the bottom plate. A pair of lugs 7 extend upwardly from the depressed top face of the bottom plate, and carry a pin 8 which serves as a pivotal mounting for a handle 9. The 55 pin may be retained in position by any suitable means such as by means of a cotter pin 10. A top plate 11 having substantially the same form as the bottom plate, is adapted to be mounted upon the bottom plate and to fit 60 into the depression 5 in the bottom plate, the top plate being of such size that there

is but little clearance left between the edges or side walls 12 of the top plate, and the inner walls 13 of the flange 11 of the bottom plate. The top plate has an aperture 15 60 formed in it, through which aperture the lugs 7 extend. The top plate has a depressed upper face 16 bounded by a circumferential flange 17 having inner walls 18 extending substantially in parallelism, upwardly from 65 the depressed face 16 of the top plate. Bolts 19 are mounted upon the bottom plate and extend through the top plate and nuts 20 mounted on the bolts secure the top plate and bottom plate upon one another. A felt 70 pad 21 is mounted upon the bottom plate, extends over the entire lower face and side wall thereof, and has its edges disposed upon the depressed face 14 of the bottom plate, said edges being secured between the top 75 plate and bottom plate. A waxing cloth 22 extends over the felt pad and has its longitudinal ends disposed within the depressed portion of the top plate. An arched spring frame 23 is mounted in the depression in the 80 top plate, and has its opposite ends seated in engagement upon the longitudinal ends of the polishing cloth 22, the tension of the frame serving to bind the ends of the polishing cloth on the top plate. One of the cross bars 24 of the spring frame has revolvably mounted on it a sleeve 25. This sleeve is adapted to rotate freely, thereby facilitating the mounting and demounting of the frame 85 on the base. 90

The cloth 22 is fitted about the lower face of the base or block, and extends over the longitudinal ends thereof, the ends of the cloth being secured by the arched spring 95 23. The waxing compound is inserted between layers of the cloth 22, and then the block is moved over the area to be waxed by means of the handle affixed thereto. The weight of the block will be sufficient, together with the friction developed by the 100 manipulation of the block, to feed the wax through the cloth 22 and to apply it to the area to be treated. After the wax has been applied to the given area, the arched frame is lifted and the cloth containing the wax 105 is removed, and the block then manipulated over the said area, the felt pad polishing the same.

What I claim is:

1. In a floor waxer and polisher, the combination of a base comprising a top and a bottom plate both of which have depressed

upper faces, the top plate being adapted to seat in the depression in the bottom plate, means to secure the plates upon one another, and an arched wire frame adapted to seat in the depression in the top plate.

2. In a floor waxes and polisher, the combination of a base comprising top and bottom plates, the top plate being adapted to be mounted on the bottom plate, a felt pad mounted on the bottom plate and having its edges secured between the plates, means to secure the plates upon one another whereby the edges of the felt pad are clamped between the plates, the top plate having a depression in its upper face, a fabric strip extending from one end of the depression, over

the lower face of the felt pad, and terminating at the other end of the depression, and an arched spring frame adapted to be sprung into, and to have its ends held, by the arch, against the ends of the fabric and the end walls of the depression. 20

3. As a new article of manufacture, a spring arch retaining frame comprising cross bars, means connecting the cross bars, 25 and a sleeve revolvably mounted on one of the cross bars.

In testimony whereof, I have hereunto subscribed my name this 16th day of Feb., 1922.

ALFRED S. BOYLE.
